SURFACING MACHINE

Wade H. Wineman, Michigan City, Ind., assignor
to Sullivan Machinery Company, a corporation
of Massachusetts

Application October 17, 1929. Serial No. 400,311

12 Claims. (Cl. 51—177)

This invention relates to an improved method and apparatus for surfacing concrete or other artificial stone. More particularly, from one of its aspects, this invention relates to a grinding device which is power driven, and may be employed for grinding the surface of concrete or other artificial stone.

An object of this invention is to provide an improved surfacing machine for use in grinding the surface of concrete or other rock-like material. A further object of this invention is to provide an improved grinding mechanism which may be power driven, and which is adapted to finish the surfaces of roadways, side-walks, floors or other hard surfaces formed of concrete or other rock-like material. A further, and more specific object of this invention is to provide an improved grinding head for a surfacing machine. Still another object of the invention is to provide an improved method of grinding or smoothing rough surfaces. Further objects of this invention will become apparent in course of the ensuing description; and will be more particularly pointed out in the appended claims.

For purposes of illustration there is shown a preferred embodiment of the invention in the accompanying drawings, in which

Fig. 1 is a view in side elevation of a machine which illustrates one embodiment of the invention.

Fig. 2 is a vertical sectional view through the left portion of the machine shown in Fig. 1.

Fig. 3 is a plan view showing a detail of the support for the grinding mechanism of the machine, a portion of one of the bearings being broken away.

Fig. 4 is a sectional view of one of the blocks which constitutes an element of the grinding head, the view being taken on line 4—4 of Fig. 5.

Fig. 5 is a plan view of the grinding head proper and is taken on line 5—5 of Fig. 2.

Fig. 6 is a horizontal section taken on line 6—6 of Fig. 2 and shows both the grinding head, and the guard surrounding the same.

Fig. 7 is a sectional detail view showing the grinding head attached to its driving shaft with a tight fit.

Fig. 8 is a modified arrangement for attaching the grinding head to its driving shaft, in which provision is made for a slight amount of universal motion of the grinding head with respect to the shaft.

In the illustrative embodiment of the invention disclosed in these drawings, there is shown a truck or frame 10 mounted on three wheels: a

caster wheel 11 and a pair of wheels 12 of the ordinary type. Above the wheels 12 is mounted an internal combustion engine 13 which drives the grinding head 14, being connected to the same by driving gearing 15 enclosed in the casings 16 and 17.

The caster wheel 11 is mounted in a yoke 18 which is pivoted at 19 within a lug 20 carried by a transverse bar 21 (see Fig. 3). Journals 22 are provided for rotatably mounting the bar 21 in the frame of the truck 10. A lever 23 may be inserted in an opening 24 in the bar 21 so as to rotate the latter. An arm 25 projects radially from the bar 21 and is perforated at 26 in its outer end. When the bar 21 has been rotated by pushing down the lever 23, a bolt 27 may be passed through the perforation 26 so as to engage beneath the frame 10, and hold the caster wheel in operative position. When the operator wishes to grind the surface of a side-walk, or other similar surfaces formed of concrete or other artificial stone, the lever 23 is pressed downwardly sufficiently to permit the bolt 27 to be withdrawn. The caster wheel 11 is then elevated or latched in elevated position (as shown on dotted lines in Fig. 2) by passing the bolt 27 through the perforation 26 so as to engage above the frame 10.

A head block or casing 30 is provided with a bore 31, within which is housed the driving shaft 32 for the grinding mechanism, ball bearings 33 being provided adjacent the upper and lower extremities of the bore 31 for maintaining the shaft 32 in proper alignment. A collar 34 is screwed onto the shaft 32 adjacent the lower ball bearing 33 to hold the latter in position, and likewise to seal the bore 31 and prevent access of dirt to the bearings. A bevel gear 35 is secured to the upper end of the shaft 32, this gear being driven by a small bevel pinion 36 fixed to a shaft 37 rotatably mounted by means of ball bearings 38 in the casing 16. The shaft 37 is driven by a spur gear 39, with which meshes a pinion 40 secured to a shaft 41, which is driven by the engine 13. The end of the shaft 41 adjacent the pinion 40 is rotatably mounted, by a ball bearing 42, in the casing 16. The casing 17 comprises a cover 43 which may be removed to secure access to the bevel gearing; and the casing 16 comprises a cover 44 which may be removed to secure access to the spur gear 39 and pinion 40. The casings and the block 30 are bolted at 45 to the forward end of the frame 10.

The head block 30 includes a depending cylindrical portion 47; and a sleeve 46 surrounds

this portion 47, and is rotatable relative to the same. The upper portion of the sleeve 46 is formed as a bevel gear 48, it being evident that the gear 48 may, if desired, be a separate gear secured to the sleeve 46. A bevel pinion 49 is secured to the lower end of a shaft 50 which is rotatably mounted in the head block 30; and a hand wheel 51 is provided for rotating the shaft 50. A plurality of arms 52 (see Fig. 6) extend 5 downwardly and outwardly from the sleeve 46; and a guard member 57 is loosely carried by the lower ends of these arms. A bore 58 is formed 10 in the lower end of each arm; and a rod 59 is disposed in each bore. Each rod 59 is a loose fit 15 for its bore 58, and is slideable relative thereto, but cannot drop out of the bore, since downward movement is limited by a pin 60 in the upper end of each rod 59. The lower ends of the rods 20 are secured to the guard member 57. To prevent the sleeve 46 from sliding downwardly on the cylindrical portion 47, a collar 61 is screwed onto the lower end of the portion 47, a set screw 62 being provided to prevent separation of the two members. It will thus be apparent that the collar 25 46 rotates in sliding engagement with the upper surface 63 of the collar 61.

The grinding mechanism includes a grinding head 65 shown in plan in Fig. 5, it being constructed in this embodiment as a cruciform member, each of the four arms 78 of which carries a grinding block 66. Each block 66 is secured to its respective arm by a bolt 67. These bolts are disposed at an angle of approximately 45° with the horizontal due to a corresponding twist 30 in each arm 78, and the block 66 is disposed at a complementary angle, the lower portion of the block 66 being beveled so as to provide a horizontal grinding surface 68. The grinding head 65 may be fixedly secured to the shaft 32 in the manner shown in Fig. 7. In such case, the lower 35 end of the shaft 32 is squared, as indicated at 70; and the socket 71 in the head 65 is correspondingly squared. A bolt 72 is passed through both the head 65 and the shaft 32, and secures the head in place on the shaft. With this type of head, the grinding surfaces 68 are rotated in fixed relation with respect to the axis of the shaft 32.

Where it is desired to have the grinding head 40 conform to the inequalities in the surface which is being ground, a connection such as is illustrated in Fig. 8 may be employed. In this case the squared end 74 of the shaft 32 does not fit tightly within the similarly squared opening 75 45 in the head 65. This arrangement permits a certain amount of play between the head 65 and the shaft 32. The perforation 76 in the shaft 32 which receives the bolt 72 is larger than the bolt, and provides a certain amount of play between the bolt and shaft 32. With this arrangement the head 65 has a limited amount of play 50 in all directions to permit universal motion of the head 65 to a limited extent, so that a surface which is not exactly at right angle to the axis of the shaft 32 may be ground.

In the use of my improved grinding mechanism, a sludge composed of water and an abrasive material is employed under the rotating head. This abrasive material may comprise water and sand, or the cuttings from the material being surfaced. If desired metallic shot may be added to the abrasive material. Since centrifugal force would tend to work the abrasive material from under the grinding head, the guard 55 is provided to collect the same as it is thrown

outwardly. An opening 77 in the guard member 57 permits the operator to move the machine over the surface being ground, and collect the sludge beneath the grinding head. The guard 57 may be rotated by the operator by 60 means of the handle 51, and the opening 77 turned in the direction of movement of the machine. The guard 57 rests directly on the surface, and is free to adjust itself to the surface. Thus, as the machine is moved from place to place to treat various portions of the surface, the sludge is carried along by the guard 57; and if any has been deposited on other portions of the surface, the same may be brought back within the guard 57 through the opening 70 90 77. The blocks 66 are easily replaceable as the same are worn down. It is obvious therefore that I have provided a surfacing machine which is easily operated, and which retains the abrasive material under the grinding head in an efficient manner.

While there is in this application specifically described one embodiment which this invention may assume in practice, it will be understood that this embodiment of the same is shown for 100 purposes of illustration and that the invention may be modified and embodied in various other forms without departing from its spirit or the scope of the appended claims.

What I claim as new and desire to secure by 105 Letters Patent is:

1. In a surfacing machine, a grinding head rotatable on a vertical axis, a guard surrounding, to a major extent, said head but leaving a substantial opening, and means for rotating said 110 guard, there being a lost motion connection vertically between said guard and said rotating means.

2. In a surfacing machine, a wheeled truck, a grinding head rotatable on a vertical axis 115 mounted in one end of said truck, a member for guiding said truck, said member being manually rotatable by the operator, a guard surrounding, to a major extent, said head but leaving a substantial opening, and means actuated by said 120 manually rotatable member for rotating said guard, there being a lost motion connection vertically between said guard and said rotating means.

3. In a surfacing machine, a wheeled truck, 125 a head block secured to said truck, a vertical shaft rotatably mounted in said head block, a grinding head mounted on one end of said shaft and driven thereby, a sleeve rotatably mounted on said head block, said sleeve being substantially 130 coaxial with said vertical shaft, a guard for said head rotated by said sleeve, there being a lost motion connection vertically between said guard and said sleeve, and manually operable means for rotating said sleeve.

4. In a surfacing machine, a wheeled truck, a head block secured to said truck, a vertical shaft rotatably mounted in said head block, a grinding head mounted on one end of said shaft and driven thereby, a sleeve rotatable on the 140 axis of said vertical shaft, a plurality of depending arms carried by said sleeve, a guard for said head operatively connected to said arms to be rotated by said sleeve, there being a lost motion connection between said guard and said 145 sleeve whereby said guard may rest on the surface being abraded during normal operation of the machine, and manually operable means for rotating said guard.

5. In a surfacing machine, a wheeled truck, 150

- 5 a grinding head rotatable on a vertical axis mounted in one end of said truck, a guard surrounding, to a major extent, said head but leaving a substantial opening, and means for rotating said guard, there being a lost motion connection vertically between said guard and said rotating means. 80
- 10 6. A grinding head structure for surfacing machines including a support, a head mounted for rotation on said support and having grinding elements on its bottom surface, and a guard mounted on said support for vertical and rotary adjustment relative thereto and encircling, to a major extent, said head but leaving a substantial lateral opening. 85
- 15 7. A grinding head structure for surfacing machines including a support, a head mounted for rotation on said support and having grinding elements on its bottom surface, a guard mounted on said support and encircling, to a major extent, said head but leaving a substantial lateral opening, and means for adjusting said guard relative to said support to change the position of said opening with respect to said head. 90
- 20 8. A grinding head structure for surfacing machines including a support, a drive element journaled thereon, a grinding head connected to said drive element, a guard encircling said head and engaging the surface to be ground, and a connection between said guard and support permitting free movement of said guard in a vertical direction to thereby adjust itself automatically to the irregularities of the surface being ground. 95
- 25 9. A grinding head structure for surfacing machines including a support, a drive element journaled thereon, a grinding head connected to said drive element, a guard encircling said head and 100
- 30 10. A grinding head structure for surfacing machines including a support, a grinding head rotatably mounted on said support, a guard rotatably mounted on said support and encircling said head to a major extent but leaving a lateral opening, and means operable at will for rotating said guard relative to said support to change the position of said opening with respect to said head. 105
- 35 11. A grinding head structure for surfacing machines including a support, a grinding head rotatably mounted on said support, and a guard encircling and rotatable relative to said head and mounted on said support for rotation about the axis of said head and independently of the latter, said guard resting on the surface to be ground and supported thereby during adjustment thereof. 110
- 40 12. A grinding head structure for surfacing machines including a support, a grinding head rotatably mounted on said support, a guard encircling and rotatable relative to said head and mounted on said support for rotation about the axis of said head and independently of the latter, and means for rotatably mounting said guard on said support, said guard being adjustable inwardly and outwardly relative to said grinding means. 115
